FOLDING BOX MACHINE

Thomas R. Baker, Sunnyvale, and Frank M. Lefief, San Francisco, Calif., assignors to Bemiss-Jason Machine Co., Inc., Redwood, Calif., a corporation of California

Application July 16, 1951, Serial No. 236,926

10 Claims. (Cl. 93—51)

1 This invention relates to improvements in folding box machines of the type in which flat, or nearly flat blanks of foldable sheet material, for example paperboard, are forced through a folding die by a plunger, thereby folding the blanks into hollow box form.

The invention offers particular advantages if applied to machines of the aforementioned general type which, in addition to folding the blank during its passage through the die, also perform locking operations on the blank to lock certain blank portions, such as walls, panels, tabs, or flaps together, so that these blank portions thereafter remain in box forming position without extraneous connecting means, such as adhesive, staples, rivets or the like.

However, the invention is not limited in its application to machines for the glueless assembly of folding boxes, but offers many advantages if applied to die-and-plunger machines for assembling glued boxes.

A major factor determining the economy of machines of the aforementioned character is the speed with which the machine can be operated. The folding operations involved in the setting up of self-locking boxes are quite complex, in that it is necessary not only to fold the several wall panels into their proper angular position with respect to the bottom panel, but it is also necessary to fold additional flaps and tabs into angular positions with respect to the wall panels to which they are articulated and to insert certain lock tabs into apertures or slits to form locks between the panels.

In boxes in which the locks are concealed, the assembly operations of the box include folding operations, followed by the insertion of certain lock tabs into apertures or slits. All these operations must be performed during passage of the box blank through the die, and they must be performed successively. It is therefore evident that the length of the stroke which the plunger must take in forcing the blank through the die is proportional to the number of operations to be performed on the blank. It is theoretically possible to perform quite a number of operations on the blank during its passage through the die by making the stroke of the plunger sufficiently long. From an economic point of view, however, this is undesirable because the longer the stroke, the slower the rate at which boxes can be produced by the machine.

The present invention is concerned with certain improvements which result in a reduction of the length of the stroke which the plunger

has to travel to complete a certain number of folding and locking operations on the box blank. The shortening of the plunger stroke makes it possible to increase the output of the machine by increasing its operating speed.

2 The various objects, features, and advantages of this invention will appear more fully from the detailed description which follows accompanied by drawings showing, for the purpose of illustration, a preferred embodiment of the invention. The invention also consists in certain new and original features of construction and combination of elements hereinafter set forth and claimed.

15 Although the characteristic features of the invention which are believed to be novel will be particularly pointed out in the claims appended hereto, the invention itself, its objects and advantages, and the manner in which it may be carried out may be better understood by referring to the following description taken in connection with the accompanying drawings forming a part of it in which,

25 Figure 1 is a perspective view of a box machine embodying the present invention, the machine being of the glueless interlocking type, and shown in a position in which a blank is being transferred from a magazine to the die;

30 Figure 2 is a perspective view of the box forming mechanism after completion of initial folding operations and partial insertion of the blank into the die;

35 Figure 3 is a perspective view of the mechanism and blank of Figure 2 shortly before the blank is engaged by the main plunger;

40 Figure 4 is a perspective detail view showing the main plunger and die in the position in which the locking of the panels commences;

Figure 5 is a perspective view of the mechanism of Figure 4 at an advanced stage of operation;

45 Figure 6 is a perspective view of the die mechanism turned upside down;

Figure 7 is an end view of the machine shown in Figure 1 but at a later phase of the operation;

Figure 8 is a plan view of the blank shown in the preceding figures; and

Figure 9 is a perspective view of the assembled box, as it is delivered by the machine.

In the following description and in the claims various details will be identified by specific names for convenience. The names, however, are intended to be as generic in their application as the art will permit. Corresponding reference char-

acters refer to corresponding parts in the several figures of the drawings.

In the drawings accompanying, and forming part of this specification, certain specific disclosure of the invention is made for the purpose of explanation of broader aspects of the invention, but it is understood that the details may be modified in various respects without departure from the broad principles of the invention and that the invention may be applied to other structures than the one shown.

The folding box machine shown in Figures 1 to 7 produces boxes by folding a blank and interlocking the box corners in a suitable manner to form a rigid self-sustaining box without gluing or stapling. Glueless interlocked boxes are quite popular because of their low cost, the high production rate at which they can be set up and because of the low cost and the relatively small size of the machine required for setting them up. The glueless interlock of such boxes generally comprises flaps on the side or end walls which are inserted through cuts or apertures at the corners of the box. A preferred form of lock is that in which the lock flaps are concealed so that the box presents the general appearance of a glued box.

The machine comprises a supporting framework 10 to which a base 11 is secured by bolts 12. A drive shaft 13 carrying a chain gear 14 is mounted in bearings 15 and 16. The drive shaft is driven through a chain 17 from a motor or some other suitable source of power (not shown) and carries a crank 18. A connecting rod 19 connects the crank 18 with a cross head 20 vertically movable on posts 21 and 22 on the base 11. The cross head 20 has a plunger 23 attached to it movable through the folding aperture 24 of a die 25. The axis of the die and of the plunger is substantially vertical in the illustrated form of machine. The plunger 23 has a head portion 26, secured to the cross head 20 by bolts 27. The bottom surface 28 of the plunger is substantially rectangular and approximately equal in size to the bottom panel of the box to be formed.

Turning now briefly to Figure 8 for an illustration of a representative form of box blank, the blank A comprises a bottom panel 29 to which side wall panels 30 and 31 are articulated along side fold lines 32 and 33. End wall panels 34 and 35 are articulated to the main or bottom panel 29 along end fold lines 36 and 37.

A cover panel 38 extends from the wall panel 30 along a cover fold line 39 and has a tuck flap 40 articulated to it along a hinge line 41. A window 42 is cut from the stock of the cover panel 38 and of the wall panel 30 and is suitably fitted with a sheet of transparent material 43.

The glueless interlocks for the several wall panels of the box comprise lock flaps 44, 45, 46 and 47 articulated to the wall panels 30 and 31 along fold lines 48, 49, 50 and 51. Side flaps 52, 53, 54, and 55 extend from the end wall panels 34 and 35 along fold lines 56, 57, 58 and 59. Angular cuts 60, 61, 62 and 63 are formed in the end wall panels and in the side flaps and extend preferably across the aforementioned fold lines 56, 57, 58 and 59. Dust flaps 64 and 65 are articulated to the end walls 34 and 35 along fold lines 66 and 67.

The lock flaps 44, 45, 46 and 47 are insertable into the angular cuts 60, 61, 62 and 63 and abut edges of the cuts with their locking edges 68, 69, 70 and 71, preferably in edge-to-edge position.

Returning now to Figure 1, the main plunger

23 has rectangular corner portions 72 adjacent the bottom surface 28, the corners near the top of the plunger being cut away as shown at 73 to facilitate the insertion of the lock flaps of the blank, as will later be seen.

The die 25 comprises a supporting plate 74 mounted on the base 11 by bolts 75 and 76. Four flank plates 77, 78, 79 and 80 of spring-hard sheet material are secured to the supporting plate 74 by bolts 81 and extend into the central aperture 82 of the plate in the manner of a hopper.

As is seen from Figure 6, the central aperture 82 of the plate 74 is roughly of the shape of a cross. The flank plates 78 and 80 extend far into the plate aperture and their end portions 83 and 84 are substantially parallel with each other and vertical. The flank plates 77 and 79 are relatively short and end at 85 and 86. Their general slope is downwardly continued by lower flank plates 77' and 79'. The lower flank plates 77' and 79' are fastened to transverse shafts 87 and 88. The shaft 87 is tiltably mounted in posts 89 and 90, and the shaft 88 is mounted in posts 91 and 92.

A spring 93 is attached to arms 94 and 95 on the shafts 87 and 88 and permits deflection of the flank plates 77' and 79' in a direction to enlarge the die aperture 24 when the main plunger with a box blank thereon passes through the die. The normal inclination of the flank elements 77' and 79' and the spacing of their bottommost edges 96 and 97 from each other is adjustable by arms 98 and 99 clamped on the shafts 87 and 88 by bolts 100 and 101. The arms 98 and 99 bear with their ends against the underside of the plate 74 and thus maintain the flank plates 77' and 79' in the properly inclined position under the action of the spring 93 as shown in Figure 6.

Referring further to Figure 6, it is seen that posts 102, 103, 104 and 105 are mounted in back of the flank plates 78 and 80. Shafts 106 and 107 are mounted in these posts with freedom to oscillate. Each shaft carries a pair of tuckers 108, 109, 110 and 111. The tuckers are at the corners at the die aperture 24 and are projectable towards, and retractable away from, the path of the plunger by oscillation of the shafts 106 and 107.

Actuating levers 112 and 113 are secured to the shafts 106 and 107 and normally extend into the path of the plunger. If struck by a box blank on the plunger, the levers 112 and 113 tilt the shafts 106 and 107 and project the tuckers 108, 109, 110 and 111 into the path of the plunger, as will later be described in greater detail with reference to Figure 5. Tilting of the shafts 106 and 107 is opposed by a spring 114 attached to arms 115 and 116 on the shafts 106 and 107. The extent to which the levers 112 and 113 may project into the aperture 24 may be adjusted by stops 117 and 118 against which the backs of the arms 112 and 113 normally rest under the pull of the spring 114.

The flank plates 77, 78, 79 and 80 together with their lower extensions 77' and 79' constitute the main die, and the aperture 24 bordered by these flank plates may be considered the main die aperture.

A further, or auxiliary die is provided spaced from, and in advance of, the main die. Turning to Figure 1, it is seen that four angular posts 119, 120, 121 and 122 extend above the die plate 74 and are secured thereto by bolts 123. In the illustrated form of die the posts 119, 120, 121 and

122 are of identical form. It will therefore be sufficient to describe one post.

Referring to the post 119, it is seen that two vertical wall portions 124 and 125 are joined at a corner 126. The post is recessed below its top surface 127 at 128 to provide a downwardly facing shoulder 129 against which edges of the box blank may abut for the purpose of locking the blank in partly inserted position in the auxiliary die.

The posts 119, 120, 121 and 122 border a substantially cross-shaped die aperture or space between them through which a blank must first pass before reaching the main die 25 underneath.

In passing through the auxiliary die, the blanks are subjected to certain folding operations which are thereafter supplemented or completed by the folding operations performed in the main die. An auxiliary plunger is provided which forces box blanks through the auxiliary die. In the illustrated form of machine the auxiliary plunger is combined with a blank feeding mechanism which will be described in greater detail after a brief consideration of the feeding mechanism proper.

The base 11 has a rigid gate supporting plate 133 attached to it which carries two dowel pins 131 near its upper end and a central bolt 132 on which a wing nut 133 fits. A magazine gate 134 is attached to the supporting plate 133 by means of the dowel pins 131, the bolt 132, and the wing nut 133.

The magazine gate 134 carries plates 135 from which blank supporting rods 136 extend rearwardly. A horizontal stack of blanks 137 rests on the rods 136 and the frontmost blank is retained in the gate by means of retaining plates 138, 139 and 140 which overlap the edges of the blank slightly. The magazine gate thus supports the blanks in an accurately defined position with respect to the base 11 and the die 25 thereon.

The rearmost blank of the stack of blanks is engaged by an arm 141 of a pusher 142 which travels on a prismatic track 143 and urges the blanks towards the magazine gate. The pusher 142 is advanced by a helical spring type of conveyor 144. Box blanks are individually withdrawn from the magazine gate by a suction feeder which forms the subject matter of a patent to Baker and Pagendarm No. 2,624,248 (application Ser. No. 67,612 filed December 28, 1948). The feeder will now be described in sufficient detail for a full understanding of this invention.

The suction feeder comprises a feeder arm 145 carrying a pair of suction cups 146. The arm 145 is hollow and serves as a suction duct to apply a partial vacuum to the suction cups at proper intervals. A flexible duct 147 is attached to the end 148 of the arm and leads to a suitable source of vacuum (not shown). The arm 145 is rigidly secured to a bracket 149 having an elongated guideway 150 engaging the cylindrical outer surface of a ball-bearing 151. The ball-bearing 151 is mounted on a stud 152 on a supporting plate 153 which, similar to the gate-supporting plate 130 is rigidly and permanently attached to the base 11.

The bracket 149 of the feeder arm 145 is pivotally connected to one arm of a bell crank lever 154 at 155. The bell crank lever 154 is pivotally mounted on the supporting plate 153 at 156. Its pivotal axis is substantially normal to the vertical plane in which the plunger axis and the magazine axis lie. The bell crank lever 154 has two 70

arms, one arm 157 being represented by the distance between the pivotal axes 155 and 156, the other arm 158 being represented by the distance between the pivotal axis 156 and the axis of a pin 159 at which one end of the connecting rod 160 is attached.

The other end of the connecting rod 160 is pivotally connected to a rocking lever 161 at 162. The rocking lever 161 is pivoted in the framework 10 of the machine about an axis 163 and carries a cam follower 164 which engages the periphery of a cam 165 on the drive shaft 13. The rocking lever 161 is under the action of helical compression springs 166 bearing with one end against the rocking lever proper and with the other end against a bracket 167 secured to the framework 10.

The cam 165 is fast on the drive shaft 13 and oscillates the rocking lever 161 about its axis 163. The lever 161, in turn, causes the bell crank lever 154 to oscillate about the pivot 156 to move the feeder arm 145 along a path which has three distinct portions.

There is firstly one phase of the motion during which the suction cups move towards and away from the magazine gate. During this translatory phase of the motion the suction cups approach the frontmost blank in the magazine, grasp it, and withdraw it substantially parallel to itself, whereby the edges of the blank are caused to slip past the edges of the retaining plates 138, 139 and 140. During this phase of the motion, the arm 145 of the feeder and the guideway 150 are substantially horizontal.

During the next phase of the motion the feeder arm 145 pivots about the axis of the ball-bearing 151 and swings in an arc towards the die. Figure 1 illustrates this rotatory phase of the motion, which ends when the blank A is vertically above the die.

During the third phase of the motion the feeder arm 145 moves vertically towards the die, in the same manner as a plunger. The main plunger 23 is near its highest point at this moment and out of the way of the feeder arm. The vertical motion of the feeder arm which, again, involves a translatory motion of the guideway 150 with respect to the ball-bearing 151, but in a vertical direction, is taken advantage of and utilized for performing certain folding operations on the blank by forcing the blank A into the auxiliary die between the posts 119, 120, 121 and 122.

The feeding mechanism thus becomes an auxiliary plunger and is, for this purpose, equipped 55 with folding elements which cooperate with the elements which constitute the auxiliary die.

The auxiliary plunger basically consists of an assembly of folding rules or edges or surfaces about which the box blank is folded as the blank enters the auxiliary die.

In the illustrated form of mechanism the auxiliary plunger consists of two identical sheet metal structures 168 and 169 secured to the feeder arm 145 by bolts 170. Each sheet metal structure comprises a top portion 171 from which two skirt portions 172 and 173 extend substantially at right angles. The skirt portions 172 and 173 are spaced sufficiently close to enter between the angular posts, for example between posts 120 and 121. The bottom edges of the skirt portions engage the box blank A adjacent certain score lines and act as folding rules or folding guides, about which portions of the blank are folded along such score lines.

Wing portions 174 and 175 extend at right an-

gles from the skirt portions and their bottom edges likewise act as folding rules or guides for other portions of the blank.

The surfaces of the sheet metal structures 168 and 169 which carry the folding edges are substantially parallel to the vertical surfaces of the angular posts 119, 120, 121 and 122 and cooperate with the posts in folding certain portions of the box blank.

As previously explained, the suction feeder carrying the box blank A together with the auxiliary plunger elements with which the feeder is combined moves toward and into the auxiliary die. Referring more particularly to Figures 2 and 3, it is evident that certain portions of the blank which later form the concealed corner lock strike the posts 119, 120, 121 and 122 as the auxiliary plunger moves downwardly. The side flaps 52, 53, 54 and 55 of the blank are thus folded substantially at right angles, with respect to the end wall panels 34 and 35, and in a similar manner the lock flaps 44, 45, 46 and 47 are folded with respect to the side wall panels 30 and 31 from which they extend.

At, or near the lowermost position of the auxiliary plunger and feeder the suction is relieved and the auxiliary plunger and feeder begins its return towards the magazine gate to pick up the next blank. Figure 3 illustrates this phase of the operation. The blank A is securely held in the auxiliary die by reason of the fact that the folded elements of the box blank, the lock flaps 44, 45, 46 and 47 and the side flaps 52, 53, 54 and 55 engage the downwardly facing shoulders 129 near the top of the posts.

During the return motion of the feeder towards the magazine gate the main plunger 23 descends and forces the blank through the main die 25, thereby completing the folding and locking operations on the blank. This phase of the assembly operation will now be described.

The bottom surface 28 of the main plunger strikes the bottom panel 29 of the box blank A locked in the auxiliary die (Figure 3). The wall panels 30, 31, 34 and 35 of the blank strike the flank plates 17, 17', 78, 79, 79' and 80 and assume an upright position with respect to the bottom panel 29. The side flaps 52, 53, 54 and 55 assume a position substantially parallel with respect to the side surfaces of the plunger. Preferably the plunger is recessed at 176 adjacent the corners 72 to accommodate the folded side flaps. The recess is particularly well visible in Figure 4 showing on an enlarged scale the location of the various portions of the blank, of the auxiliary die and of the main die. Due to the fact that the angular cuts 60, 61, 62 and 63 intersect the corner fold lines 56, 57, 58 and 59, the cuts open automatically when the side flaps are folded, and the lock flaps 44, 45, 46 and 47 enter the apertures thus formed.

As the lock flaps move into the open cuts they tend to encounter an increasing amount of friction, due to wedge-action of the board near the ends of the cuts. The tuckers 108, 109, 110 and 111 at the four corners of the main die are provided specifically to relieve this friction by widening the apertures while the lock flaps are being inserted.

As the plunger moves through the die, the plunger with the blank thereon strikes the actuating levers 112 and 113 (Figure 6) with the result that the tuckers are moved towards the path of the plunger. This action is particularly well shown in Figures 4 and 5, Figure 4 showing the tucker 110 at the beginning of its movement to-

wards the plunger and Figure 5 showing the tucker 110 in its fully projected position. As previously described, the corner of the plunger is cut away at 73, permitting the box blank to be readily flexed by the tucker, so that the lock flap 47 enters freely into the cut 63.

When the wall panels 30, 31, 34 and 35 reach their final position at right angles with respect to the bottom panel 29, the locking edges 63, 69, 70 and 71 (Figure 8) snap into engaging and locking position with the corresponding portions of the cuts 60, 61, 62 and 63. At the lowermost position of the main plunger the outer edges of the box blank are slightly below the bottommost edges 96 and 97 of the flank plates 17' and 79' as well as below the bottom edges of the flank plates 78 and 80. As the plunger begins its return stroke, the box blank is stripped off the plunger by these bottom edges for convenient removal from the machine in a convenient manner.

Instead of utilizing the bottom edges 96 and 97 for stripping the box from the plunger, the ends of the levers 112 and 113 may be employed for the same purpose.

Summarizing briefly the operation of the machine, the auxiliary plunger and feeder removes blanks from the magazine and deposits them in the auxiliary die thereby performing initial folding operations, particularly on the locking elements of the box blank. During this phase of the operation the main plunger is retracted. The auxiliary plunger and feeder then move out of the way of the main plunger which forces the blank through the main die and completes the folding and locking operations.

Thus the total stroke required for setting up the box is split into two portions, the first portion of the stroke being performed by the auxiliary plunger and feeder, the second portion of the stroke being performed by the main plunger. The length of the stroke of the main plunger can thus be made relatively short permitting extremely rapid operation of the machine.

The invention has been described and explained by reference to a specific form of machine. It will be apparent, however, to persons skilled in the box machine art that numerous modifications, additions, omissions, substitutions and other changes may be made without departing from the principles and the spirit of this invention.

What is claimed is:

1. A device for setting up folding boxes from flat box blanks, the device comprising, a main plunger; a main die having a die aperture through which said main plunger is movable; an auxiliary die in advance of said main die; a combined auxiliary plunger and feeder, including suction means for grasping a blank; a magazine having a withdrawal gate through which blanks are withdrawn; means for mounting said main plunger for straight line movement through said dies; means for supporting said auxiliary plunger on the side of the path of the main plunger with freedom of oscillatory movement about an axis angular with regard to the main plunger axis, into and out of the path of the main plunger and with freedom of translatory movement towards, and away from, said dies, and towards, and away from, said gate; and means for moving said main plunger and said auxiliary plunger in timed relationship.

2. A blank feeding and box forming unit for paperbox machines the unit comprising; a base; a magazine gate mounted on said base; a box forming die mounted on said base, said die hav-

ing a main die portion including elements bordering a main die aperture, and an auxiliary die portion in front of said main die portion; a main plunger; means on said base, including a plunger track for guiding said main plunger for movement through said auxiliary die portion and said main die aperture; a feeder head including suction means; folding rules on said feeder head cooperating with said auxiliary die portion for folding a box blank grasped by said suction means when said head enters said auxiliary die portion; an arm for supporting said feeder head; means on said base for supporting said gripper arm on the side of the path of the main plunger with freedom of oscillatory movement about an axis angular with regard to the main plunger axis, into and out of, the path of the main plunger and with freedom of translatory movement towards and away from, said dies, and towards and away from, said gate; and means for moving said main plunger and said gripper arm alternately towards said dies in timed relationship.

3. A device for setting up into hollow box form flat box blanks having a main panel, wall panels articulated to the main panel and flaps articulated to said wall panels, the device comprising, a die having first folding elements for engaging and folding said wall panels, said first elements bordering a main die aperture; auxiliary folding elements for engaging and folding said flaps, said auxiliary folding elements being mounted on said die in advance of said main die aperture; a magazine having a withdrawal gate through which blanks are withdrawn; a main plunger movable past said auxiliary folding elements and through said main die aperture; a feeder head having suction elements for grasping a box blank; folding rules on said head, said rules extending substantially parallel to said auxiliary folding elements and bearing against the surface of a flat blank grasped by said suction elements; an arm supporting said feeder head; means for pivotally mounting said arm alongside the path of the main plunger with freedom of oscillatory movement about an axis normal to the main plunger axis, into, and out of, the path of the main plunger and with freedom of translatory movement towards, and away from said die and towards and away from, said gate; and means for moving said main plunger and said arm alternately towards said die in timed relationship.

4. A device for setting up into hollow box form flat box blanks having a main panel, wall panels articulated to the main panel and flaps articulated to said wall panels, the device comprising, a die having first folding elements for engaging and folding said wall panels, said first elements bordering a substantially rectangular main die aperture; auxiliary folding elements for engaging and folding said flaps, said auxiliary folding elements being mounted on said die at the corners of said aperture and in advance of said main die aperture, said auxiliary folding elements having abutment portions projecting towards said aperture for engaging edges of the folded flaps of a blank moved into the space between said auxiliary folding elements and preventing withdrawal in a direction away from the aperture; a main plunger movable past said auxiliary folding elements and through said main die aperture; a feeder head having suction elements for grasping a box blank; folding rules on said head, said rules extending substantially parallel

to said auxiliary folding elements; and means for moving said main plunger through said main die aperture and for moving said head towards said main die aperture and past said auxiliary folding elements in alternating order.

5. A device for setting up into hollow box form flat box blanks having a main panel, wall panels articulated to the main panel and flaps articulated to said wall panels, the device comprising, a die having first folding elements for engaging and folding said wall panels, said first elements bordering a substantially rectangular main die aperture; auxiliary folding elements for engaging and folding said flaps, said auxiliary folding elements being mounted on said die in advance of said die aperture, said auxiliary folding elements having blank engaging surfaces substantially parallel with the sides of the die aperture; a main plunger movable past said auxiliary folding elements and through said main die aperture; a feeder head having suction elements for grasping a box blank; folding rules on said head, said rules being substantially L-shaped in plan view, in the position in which the head rests over said die aperture, the vertex of the L being at the corners of the aperture and the legs of the L pointing away from said aperture substantially in line with the sides of the aperture; retaining means mounted on said die for engaging and retaining a partially folded blank against withdrawal from said die during movement of said feeder head away from said die; and means for reciprocating said main plunger through said main die aperture and for reciprocating, alternately with said plunger, said head past said auxiliary folding elements and said retaining means.

6. A device for setting up into hollow box form flat box blanks having a main panel, wall panels articulated to the main panel and flaps articulated to said wall panels, the device comprising, a die having first folding elements for engaging and folding said wall panels, said first elements bordering a substantially rectangular main die aperture; auxiliary folding elements for engaging and folding said flaps, said auxiliary folding elements being mounted on said die substantially at the corners of said main die aperture and in advance of said main die aperture; a main plunger movable past said auxiliary folding elements and through said main die aperture; a feeder head having suction elements for grasping a box blank; folding rules on said head, said rules extending substantially parallel to said auxiliary folding elements in a position to bear against the surface of a flat blank grasped by the feeder head; movable members on said die substantially at the corners of said die aperture, said movable members being projectable into the path of said main plunger and against a blank folded about the plunger to flex said blank; means for biasing said members towards their retracted position; means operable by the plunger for moving said members into projected position during passage of said main plunger through said die; an arm supporting said feeder head; means for pivotally mounting said arm alongside the path of the main plunger with freedom of oscillatory movement about an axis normal to the main plunger axis, into, and out of, the path of the main plunger and with freedom of translatory movement towards, and away from said folding element towards and away from a point of blank delivery; and means for moving said

main plunger and said arm alternately towards said folding elements in timed relationship.

7. A device for setting up into hollow box form flat box blanks having a main panel, wall panels articulated to the main panel and flaps articulated to said wall panels, the device comprising, a die having first folding elements for engaging and folding said wall panels, said first elements bordering a substantially rectangular main die aperture; auxiliary folding elements for engaging and folding said flaps, said auxiliary folding elements being mounted on said die substantially at the corners of said main die aperture and in advance of said main aperture, said auxiliary folding elements having abutment portions in their sides for engaging edges of the folded flaps of a blank moved into the space between said auxiliary folding elements and retaining the partially folded blank between said auxiliary folding elements; a main plunger movable past said auxiliary folding elements and through said main die aperture; said plunger having recessed corners; a feeder head having suction elements for grasping a box blank; folding rules on said head, said rules extending substantially parallel to said auxiliary folding elements in a position to bear against the surface of a flat blank grasped by said feeder head; movable members on said die substantially at the corners of said die aperture, said movable members being projectable into the path of said main plunger towards said recessed plunger corners to deflect portions of a blank on said plunger into said recessed corners; means for biasing said members towards their retracted position; means operable by the plunger for moving said members into projected position during passage of said main plunger through said die; and means for moving said main plunger through said main die aperture and for moving said head towards said main die aperture and past said auxiliary folding elements, in alternating order.

8. A device for setting up folding boxes from flat box blanks, the device comprising, a main plunger; a main die having a die aperture through which said main plunger is movable; an auxiliary die in advance of said main die; a suction gripper; a gripper arm carrying said gripper; a magazine having a withdrawal gate through which blanks are withdrawn; blank folding elements on said gripper arm in a position to bear against the surface of a flat blank grasped by said gripper, said elements cooperating with said auxiliary die to fold the flat blank when said elements enter said auxiliary die; means for mounting said main plunger for straight line movement to said dies; means for supporting said gripper arm on the side of the path of the main plunger with freedom of oscillatory movement about an axis angular with regard to the main plunger axis, into and out of, the path of the

main plunger and with freedom of translatory movement towards and away from, said dies, and towards, and away from, said gate; and means for moving said main plunger and said gripper arm alternately towards said dies in timed relationship.

9. A pre-flexing mechanism for box blanks having scores, the mechanism comprising, a die having an aperture through which the box blank is moved; at least one blank engaging projecting member on said die in advance of said die aperture; a feeder head movable towards, and away from, said aperture, said head including at least one suction cup for grasping the blank; a folding element mounted on said head, said folding element having a blank engaging portion lying in substantially the plane of the mouth of said suction cup; and means for moving said feeder head towards said aperture sufficiently far for the said engaging portion to move past the top end of said projecting member closer towards said aperture than the top of said projecting member.

10. A pre-flexing mechanism for box blanks having scores, the mechanism comprising, a die having an aperture through which the box blank is moved; at least one blank engaging projecting member on said die in advance of said die aperture, said projecting member having a side surface; a feeder head movable towards, and away from, said aperture, said head including at least one suction cup for grasping the blank; a folding rule mounted on said head, said folding rule having a blank engaging portion lying in substantially the plane of the mouth of said suction cup and substantially parallel to the side wall of the projecting member; and means for moving said feeder head towards said aperture sufficiently far for said engaging edge to move past the top end of said projecting member closer towards said aperture than the top of said projecting member.

THOMAS R. BAKER.
FRANK M. LEFIEF.
